UNITED STATES PATENT OFFICE.

ALBERT J. BROUILLETTE, OF WOONSOCKET, RHODE ISLAND, ASSIGNOR TO SHAMBOW SHUTTLE COMPANY, OF WOONSOCKET, RHODE ISLAND.

SHUTTLE-EYE.

1,396,555.

Specification of Letters Patent.

Patented Nov. 8, 1921.

Application filed February 12, 1921. Serial No. 444,324.

To all whom it may concern:

Be it known that I, ALBERT J. BROUILLETTE, a citizen of the United States, residing at Woonsocket, in the county of Providence and State of Rhode Island, have invented new and useful Improvements in Shuttle-Eyes, of which the following is a specification.

This invention relates to certain new and useful improvements in shuttle eyes, and pertains more especially to shuttle eyes made of porcelain.

The objection to the use of porcelain eyes is the likelihood of breakage due to the vibrations of the free portion of the shuttle, which displace the eye and cause breakage thereof, necessitating the insertion of a new eye.

The primary object of the invention is therefore to provide a structure wherein breakage of the eye is reduced to a minimum, and to also provide a structure wherein the eye can be easily and quickly threaded, and will be guarded against accidental unthreading.

Still further, the invention aims to provide a simple and economical construction and one which can be easily and reliably secured in place, and held against movement when in place.

Further and other objects will be later set forth and manifested in the course of the following description.

In the drawings:

Figure 1, is a top plan view of the invention in position in a shuttle;

Fig. 2, is a side elevation;

Fig. 3, is a section on line 3—3 of Fig. 1, and

Fig. 4, is a detail perspective view of the eye.

In proceeding in accordance with the present invention, an eye is employed which consists of a porcelain body having a thread receiving slot 1, extending axially thereof and through the bottom side of the body. As shown in Fig. 4, the outer end wall of the eye is of relatively considerable area or formation and is designed to abut against the solid wood of the shuttle S, throughout such area except as to a small inset portion 3, which lies rearwardly of the major portion of said end wall to admit of the passage of the thread in moving the latter into threaded position. A rib 4, extends axially

of the body of the eye and is received in a conforming aperture provided therefor in the wood of the shuttle. The eye has a diagonal wall 6, to assist in threading and a tail 7 against which latter a cushioning fiber washer 8, is impinged and held by a screw plug 9. In this manner the eye is securely held abutted against the shuttle wood and against the washer, and since the rib 4, prevents rotation of the eye, it will be seen that same is securely held in position.

As depicted in Figs. 2 and 3 of the drawings, the shuttle is formed with a lower ledge or wall 10, which extends across the slot 1, to prevent accidental unthreading and is also provided with a somewhat similar upper wall or ledge 11 to prevent the yarn from passing above the part 4, during the act of threading.

In operation, the thread is placed in the usual threading slot T, of the shuttle, and then moved downwardly and along the horizontal part of such slot, thence under the part 3, and into the slot 1, in which it will be held in the slot by the wall or ledge 10. In this movement, the thread from the bobbin will pass over the tail 7, from the throat of the shuttle, as is apparent from Fig. 1.

Having thus described my invention, what I claim as new and desire to secure by Letters Patent is:—

1. In a shuttle having spaced upper and lower horizontal ledges, an eye formed of porcelain and having an end abutted against the shuttle opposite to said ledges, said eye having an axial slot and an inset at said end to permit the thread to enter the slot, a tail at the opposite end of the eye, a longitudinal rib on the eye received in an opening provided therefor in the shuttle to hold the eye against rotation, a fiber washer engaged against the outer end of the tail and a screw plug engaged with the washer.

2. In a shuttle, a porcelain eye having thread receiving means and having an end abutted against the wood of the shuttle, a projection formed on the eye and receivable in a recess provided therefor in the shuttle to hold the eye against turning, a fiber washer engaged with the opposite end of the eye, and a screw plug threaded directly into the shuttle to engage and hold the washer impinged and against movement in its said relation to the eye.

3. In a shuttle, a porcelain eye having thread receiving means and having an end abutted against the body of the shuttle, a tail extending outwardly from the opposite end 5 of the eye and disposed across the shuttle throat, a fiber washer abutted against the outer end of the tail, and a screw plug threaded directly into the shuttle to hold the washer against the tail.
- 10 4. In combination with a shuttle having a transverse opening with one end partly closed and its other end open and having an extension communicating therewith, an eye in the transverse opening having a peripheral projection extending into the extension of the opening to hold the eye against rotation, said eye having one end engaged with the partly closed end of the opening, cushioning means engaged with the 15 opposite end of the eye, and a plug threaded into the open end of the transverse opening to hold the cushioning means against the eye and the projection of the latter in said extension of the opening.
- 20 25 5. In a shuttle, a porcelain eye having thread receiving means and having an axial
- rib engaged in an opening provided therefor in the shuttle to hold the eye against rotation, one end of the eye being impinged against the shuttle body, a cushioning 30 washer engaged with the opposite end of the eye, and a screw plug threaded directly into the shuttle to removably hold the washer in place and to hold said rib in its opening.
6. In a shuttle, a porcelain eye having an axial downwardly opening thread slot and having its forward end impinged against the shuttle body, said end being formed with an inset to allow the thread to enter the slot from the bottom thereof, the shuttle having 40 upper and lower guard parts, the lower one to prevent the thread leaving the slot and the upper one to limit the upward movement of the thread in threading, and means to hold the eye in position. 45

In testimony whereof I have signed my name to this specification in the presence of two subscribing witnesses.

ALBERT J. BROUILLETTE.
